UNITED STATES PATENT OFFICE.

CHARLES S. CHAMPION, OF WASHINGTON, DISTRICT OF COLUMBIA.

DESIGN FOR A SPOON.

SPECIFICATION forming part of Design No. 21,714, dated July 19, 1892.

Application filed June 23, 1892. Serial No. 437,779. Term of patent 3½ years.

To all whom it may concern:

Be it known that I, CHARLES S. CHAMPION, a citizen of the United States, residing at Washington, in the District of Columbia, have 5 invented and produced a new and original Design for Spoons, of which the following is a specification, reference being had to the accompanying drawing, forming a part thereof.

The drawing is a front elevation of a spoon, 10 showing my design applied thereto.

The main feature of my design consists in a spoon having the handle thereof formed by or bearing the representation of, first, a stand of arms composed of stacked guns, and, sec- 15 ond, a military emblem or badge.

A represents the bowl of the spoon, B guns composing the stand of arms, and C a military emblem or badge.

What I claim is—

The design for a spoon, as herein shown and 20 described.

In testimonay whereof I affix my signature in presence of two witnesses.

CHARLES S. CHAMPION.
